PNEUMATIC TICKET DISPATCH TUBE FOR
TELEPHONE EXCHANGES OR THE LIKEJohn Ernest Malcolm McGregor,
London, EnglandApplication October 20, 1932, Serial No. 638,760
In Great Britain October 12, 1931

2 Claims. (Cl. 302—2)

This invention relates to a system of pneumatic ticket dispatch tubes for telephone exchanges or the like in which tickets or dockets are transmitted through tubes from one position to another by means of rarefied or compressed air. These tubes are commonly of rectangular bore, the dimensions of which depend on the size of ticket to be transmitted; the ticket is provided with a head or sail by folding into the shape of an arrow or other means and is propelled by a current of air in the tube produced by means of a centrifugal fan or blower which maintains a slight vacuum or pressure. In the known systems the tickets are deposited in a delivery terminal from which they are removed manually or by means of electrically operated or motor driven devices, as owing to the fact that the ticket has practically no weight its impact is insufficient to enable it to automatically eject itself.

According to this invention, in a pneumatic dispatch tube system for the transport of tickets and such like light articles, the ticket or the like is by-passed out of the main stream into a guide in a discharge terminal, the guide being freely open to the air stream so that the ticket is not drawn to a side of the guide and is discharged by striking a door pivoted about a horizontal axis approximately midway of the door, the door being thus self-balanced as regards gravity and air pressures, the door being opened solely by the impact of the ticket or the like.

The action of the apparatus according to the invention for ejecting tickets is purely automatic, the tickets being ejected solely by virtue of their momentum.

The pneumatic ticket dispatch tube system according to the invention may be arranged so that a number of tickets may be simultaneously inserted in the tube at different dispatch points without loss of vacuum or pressure which would prevent the efficient operation of the system.

The dispatch terminals may be constructed so that the tickets are introduced into the tubes at a high velocity in order to prevent a number of tickets which are simultaneously transmitted from different points interfering with one another and blocking the tube.

The efficiency of the discharge terminal according to the invention does not depend within very wide limits on the value of the pressure or vacuum used in the tubes.

In the accompanying drawings:—

Fig. 1 is a front elevation of one form of discharge terminal according to the invention.

Figs. 2 and 3 show a side elevation and sec-

tional side elevation, respectively, of the discharge terminal;

Figs. 4 and 5 show front and side elevations of a dispatch terminal;

Fig. 6 shows a front elevation of another embodiment of a dispatch terminal for use on tubes where the traffic is small or there are few intermediate dispatch points.

Fig. 7 is a side elevation of a modified construction of discharge terminal according to the invention.

Fig. 8 is a view looking in the direction of the arrow in Fig. 7.

The dispatch terminal, as shown in Figs. 4 and 5, is provided with a wire or similar open guide 8 into which the folded ticket is inserted. A sliding rack 9 engaging with a pinion 10 is arranged to rotate the two rollers 11, 12 through gearing so that the ticket is gripped and thrust into the tube 4 through the guide 13. In the figures a sliding rack is shown provided with a spring 14, but any suitable means of revolving the rollers may be employed such as a thumb wheel. The rollers may be constructed of metal, rubber or other suitable material and are normally kept in close contact with each other by means of springs 15, the springs allowing the rollers to open sufficiently to allow the tickets to pass. This construction of dispatch terminal allows a minimum of leakage from the tube when the ticket is inserted and enables a number of dispatch terminals to be operated simultaneously without seriously affecting the pressure conditions in the tube. Where the tube carries little traffic, or there is only one dispatch point, a simpler form of dispatch terminal as shown in Fig. 6 may be used. This terminal is provided with a hinged cover plate 16 normally kept closed by a spring 17 and opened only for the insertion of a ticket.

The ticket once inserted in the tube 4 is propelled in the usual way along the tube by the action of the air and is led to a discharge terminal 2 shown in detail in Figs. 1, 2 and 3. The terminal is provided with a wire guide 18 through which the ticket passes. A door 19 is provided with pivots 20 and is accurately adjusted so that it is very slightly out of balance as regards air pressures and gravity in order to keep it in the closed position. When the ticket passing through the guide 18 strikes the door 19, the latter swings on its pivots and allows the ticket to emerge, the door then automatically swinging back to the closed position. The door is made of aluminium or other suitable material. A rubber or similar

stop 21 is fitted so as to limit the opening of the door and to assist its closing. Leakage past the door is prevented by a seal of leather or other suitable material. This seal may be placed at 5 both the upper and lower half of the casing or on the upper half only. In order to prevent any lateral force on the ticket which would tend to jam it against one side of the tube at the point where the latter is diverted from the main stream 10 of air, air chambers 22 are provided on each side of the terminal and are open to the interior of the terminal through holes 23. The air passing through the tube 4 passes through these holes 23 on each side of the terminal, leaving the ticket 15 unaffected and emerges from the terminal and into the tube 4 through the opening 24.

In the modified construction shown in Figs. 7. and 8, the ticket guide is formed by a straight extension 30 of the tube 4 and is provided with 20 cut away portions or ports 32 (Fig. 7) at the lower front end, a slide 26 mounted on the guide being provided to control the area of such ports.

The vacuum service pipe 40 communicates with the terminal box behind the guide 30, and through 25 the ports 28 with the side chambers 22. These side chambers 22 communicate with the interior of the terminal by way of the holes 23. The door 19 is pivoted at 20 as in the previous construction and a resilient back stop is provided for 30 the door at 31. A plate 25, preferably having a backing of felt or like material is secured to the casing by a screw and slot connection 29 so that it is adjustable to vary the effective area of the upper half of the door 19 exposed to the atmosphere for the purpose of adjusting the balancing 35 of the door. In the design of this door two conditions have to be met, the open and closed conditions, the balance in these two cases being different. The door is hinged approximately on 40 the centre line and balanced so that, when open, the forces acting, i. e. atmospheric pressure, vacuum, inrush of atmospheric air, outflow of air from the tube, and gravity, are so resolved that the door promptly closes. In the closed condition it has to be balanced against the static forces 45

of the various air pressures, gravity and the pressure due to the moving column of air in the tube. The area of the top half of the door exposed to the atmosphere is therefore modified by contact with its seat, which may be constructed as an 5 adjustable slide to vary this area, until the balance is such that the door opens under the impact of the ticket.

Inspection doors giving access to the side chambers 22 are provided at 27. It will be understood 10 that the discharge terminal according to this invention provides a simple and efficient device whereby tickets or the like are discharged automatically without cutting off the vacuum.

Although the invention has been described in 15 connection with tubes of rectangular bore, such as are commonly used in pneumatic ticket dispatch tube systems, it is, of course, equally suitable for a pneumatic dispatch system having tubes of other cross-section.

What is claimed is:

1. A pneumatic tube system comprising a tube, a discharge terminal having an opening, a pivotally supported door for said opening, said door being unbalanced so as to return to a closed position where it becomes re-balanced so as to open on the impact of a ticket dispatched through said tube and a resilient stop to limit the opening of the door and to assist in its closing.

2. A pneumatic tube system comprising a tube, a discharge terminal having an opening, a door for said opening, said door when closed being balanced solely by gravity and air pressure so as to be adapted to open solely by the impact of a ticket dispatched through said tube, and when opened being unbalanced so that it will immediately close solely by gravity and air pressures; and an adjustable strip associated with said discharge terminal adjacent the edge of said door whereby the area of the door exposed to air pressures when the door is closed may be varied so that when the door moves from the open to the closed position it becomes re-balanced.
